RAIL CHAIR

Robert Hill, Oakville, Ontario, Canada

Application December 31, 1931, Serial No. 584,230
In Canada November 7, 1931

15 Claims. (Cl. 238—304)

This invention relates to rail chairs and is along the line of my co-pending United States patent applications Ser. No. 555,773, filed August 7th, 1931 and Ser. No. 555,774, filed August 5 7th, 1931.

The objects of the invention are to provide a simply constructed, durable and reliable rail chair that can be readily manufactured and placed on the market in quantities at comparatively low cost.

Another object is to provide a rail chair fashioned from any suitable material, rolled plate, malleable iron or steel castings and other materials.

15 The essential features of the invention comprise a tie plate having on its top a rail bearing surface, a transversely arranged permanent rail engaging shoulder and spaced therefrom, forming a seat for the base of a rail therebetween, a rail abutting, transversely arranged shoulder, adapted to loosely hold a rail securing or keeper member, a self-locking key for engagement with the shoulder and with the keeper, and simultaneously impinging on the keeper, to 20 operatively and flexibly secure a rail in the seat and oppose overturning of the securing member.

The invention will be best understood by reference to the following description when taken in connection with the accompanying illustration 30 of one specific embodiment thereof while the scope of the invention will be more particularly pointed out in the claims.

Referring now to the drawings and to the embodiment therein disclosed for illustration purposes only, and in which like numerals of reference indicate corresponding parts in each figure.

Fig. 1 is an end view, partly in section, of the plate with a rail section seated and secured therein.

40 Fig. 2 is a top plan view showing the locking key in dotted lines, in position.

Fig. 3 is a detail of the locking key before being inserted.

Fig. 4 is an enlarged detail of the clamping member detached.

Fig. 5 is an enlarged detail, partly in section, of a modified form of key in position.

Fig. 6 is a similar view of another modified form of key.

50 Fig. 7 is a similar view of yet another modified form of locking key.

Fig. 8 is a further modified form of a locking key.

55 Fig. 9 is a similar view of a locking key substantially L-shaped.

Fig. 10 is a similar view of a wedge-shaped locking key.

Fig. 11 is a detail of the "follower" for injecting and ejecting the locking key.

Referring more particularly to the drawings, A, 60 designates a rail or tie plate as a whole, and B, a rail section seated therein. The plate A, is formed from rolled plate, malleable iron, steel castings or other materials and has integral therewith a permanent transversely extending wall or shoulder 10, formed to abut the edge 11, of the rail base C, and then bent to overlap, in spaced relationship thereto, the top surface 12, of the rail base, as at 13. Spaced from this shoulder or wall 10, and adapted to abut on the 70 base of the rail is a second transversely extending shoulder 14, bent in the same direction, as at 15, as the wall 10, to form a guideway 24, for a locking member or key 22 and for engagement with a retaining or keeper member as hereinafter more fully referred to. The surface or chair portion 16, between the walls 10, and 14, and on which the base of the rail rests may be flat or, as shown, in the present example, slanted from the rail abutting wall 14, to the permanent 75 retaining wall 10. It should, however, be noted that the underside of the plate A, is adapted to rest upon the ties and is secured thereto, in well known manner, as by lag screws 30.

The wall or shoulder 14, has an opening 17, 80 therein extending through the plate A. This opening is designed to hold the rail securing member 18, an example of which is illustrated in Fig. 4, consisting of metal formed, with a stem, 13' and a head portion 19, conforming to the 90 contour of the bent wall 14 and adapted to overlap the shoulder 14 and protruding in lip form, as at 20, to loosely engage with the rail base C. The stem portion is provided with a hole or passageway 21, having formed therein a projection 29, (see Fig. 2). This passageway is designed to register with the guideway 24, in the shoulder 14, when the member 18, is placed in position. Furthermore, it should be noted that the stem 13' of this retaining or keeper 95 member 18, loosely engages with or is in anti-tipping contact with the plate. Again, the plate opening 17, for the retaining member may have its inner edge slightly underlying the rail edge (see Fig. 10), thus tending to permit limited rotation of the retaining member. In short, the keeper conforming at the top to the contour of the bent wall 14, and protruding in lip form over the rail base and normally held in spaced relationship thereto and the anti-tipping en- 100

gagement of the stem of the keeper with the opening in the tie plate provide, in combination, with the self-locking key, for flexibility and abnormal rotation of the keeper. Associated with the shoulder 14, and the securing member 18, is a most important and essential member in the form of a locking-pin or key 22, designed to be inserted in the guideway 24, in the rail abutting shoulder 14, and to pass through the hole 21, and beyond the projection 29, in self-locking engagement therewith, to retain the member 18, in flexible resilient securing position relative to the rail A, as hereinafter more fully described.

15 The locking pin 22, is so bent intermediately that once it is driven home any attempt to tamper with it will cause it to break or split.

The locking pin or key 22, is made of spring steel or other suitable material and is intermediately offset, as at 25, one end being straight and the other end being outwardly bent, as at 26, to abut against the member 18, and automatically resist tipping of the same in operation and thereby retaining this member in balanced, spring securing position relative to the base C, of the rail. Furthermore, when the member 22, is inserted and driven by the "follower" 31, into the shoulder 14, and through the member 18, it will automatically, being of spring steel or other suitable material, partially straighten out past the projection 29, to protrude, becoming self-locking as it is driven home, and through the bent end, impinging on the outer surface of the securing or rail holding member 18, and acting as a lever to prevent this member tipping unduly on weight passing over the rail. Also, as above mentioned, imparting to the member 18, a spring effect while securing and retaining said member in operative position relative to the rail. In short, while providing flexibility, automatically balances the securing member in position. The formation of the locking pin or key 22, with the offset body portion and one end suitably bent relative to said body, ensures stability and minimizes torsion and thereby any possibility of the pin becoming displaced when locked in engagement with the projection 29.

Various modified forms of this locking member, which it should be noted can be used with the construction disclosed in my previously cited co-pending United States applications, as shown in the accompanying drawings, Figs. 5 to 10 inclusive, but it will be noted that the offset formation 25, is substantially preserved in each of them.

With regard to the walls or shoulders 10, and 14, it should be mentioned that the formation of the latter materially facilitates the insertion of the rail section onto the bearing surface or chair portion 16, into loose engagement with the permanent wall 10, and that when this is accomplished it is only necessary to insert the securing member in the opening 17, and then insert by means of the "follower" 31, the self-locking pin or key 22, as previously described, when the operation of placing the rail in the chair and automatically and resiliently locking it in a secure position therein, is accomplished. To further facilitate the locking of the member 18, in the shoulder 14, the passageway 21, may also be varied. Once the locking member 22, has been inserted it is practically impossible to remove it except with the "follower."

75 Referring to the several modified forms of

the locking pin or key 22, as disclosed. In Fig. 6, the offset portion 25, is still preserved while the outwardly bent end 26, is extended over the member 18. In Fig. 7, as shown, the bent end 26, engages with a slot or recess in the member 18, or, as shown in Fig. 5, impinges against said member. In Fig. 8, the member 22, is curved and in Fig. 9, it is shown as slightly offset and with one end bent substantially at right angles, as at 28, while in Fig. 10, the locking member 18, is wedge-shaped. This member 22, and the various modifications thereof is adapted to be used in the construction disclosed in my co-pending United States applications, as well as in the present construction, the construction as a whole having been conceived and developed to provide a combined anti-tipping, tamper-proof key or pin in combination with the wall of a rail chair having a rail holding member therein.

From the foregoing it will be seen that applicant has provided combined anti-tipping and self-locking means for a rail holding or retaining member, of simple and durable construction that through loose engagement with the tie plate and the rail base, while engaging with and conforming to the contour of the bent wall, all combined with the self-locking means, provide for flexibility and resiliency in operation with limitation of rotation tending to resist tipping of the retaining member while permitting in combination with the loose engagement of the rail with the other bent wall, free wave motion of the rail. In short, the combination with an inwardly hooked rail retaining wall 10, and an outwardly hooked rail abutting wall 14, a detachable rail retaining member conforming to the contour of the outwardly hooked wall and loosely engaging with the plate, of a spring pin or key formed for self-locking engagement with the abutting wall 14, and the retaining member 18, and also impinging upon said member in anti-tipping engagement therewith.

The complete operation is as follows: The combined rail-plate and chair member A, having been secured in position, the rail section E, is lifted into engagement with the abutting wall 14, and allowed to glide on it onto the bearing surface or chair portion 16, when it is moved therealong engaging with the wall 10, in position. The member 18, is then placed in the hole 17, and the locking pin 18, inserted by means of the "follower" 31, in the guideway 24, of the wall or shoulder 14, and through the opening 21, and as it travels it locks, and as it does, the bent end either impinges on or otherwise, in any suitable manner, engages with, as illustrated, the outer surface of the holding member 18, acting as a lever to perform the additional functions of resisting tipping or rotation of the holding member. To withdraw the member 22, it is necessary to use the "follower."

A feature of this locking member is that while it is comparatively easy to insert it in self-locking position relative to the wall 14, and the rail holding member 18, it is almost impossible to take it out except with the "follower" and this, in combination with the wall and the rail holding member not only makes it tamper-proof, but also automatically provides for balanced resiliency and flexibility in the holding of a rail.

The member 18, is so formed relative to the head portion 19, and stem 13", that it can be readily reversed to still effectively overlap

the base of a rail and in spaced relation thereto. Various forms of the apparatus described will suggest themselves to those skilled in the art; it is, therefore, not intended that the present 5 application should be limited to any particular form of construction; modifications may be made in the apparatus above described within the scope of the claims, without departing from the spirit or scope thereof.

10. What I claim for my invention is:

1. A rail chair comprising a tie plate having on its top a transversely arranged rail retaining shoulder and an apertured rail abutting shoulder in spaced relation, a rail bearing surface between said shoulders to form therewith a chair for the rail, a rail retaining member or keeper detachably associated with the rail abutting shoulder and said plate and formed with an opening therethrough having an abutment therein, a locking pin or key formed for self-locking engagement with the rail abutting shoulder and the rail retaining member.

2. A rail chair comprising an apertured tie plate having on its top a transversely arranged rail retaining wall and a transversely arranged rail abutting wall in spaced relationship, a rail bearing surface intermediate of said walls, a separate rail retaining member conforming to the contour of the rail abutting wall and adapted to loosely engage with said wall and with the base of a rail in the chair, a pin of resilient material intermediately offset and suitably bent for self-locking engagement with the retaining member and the rail abutting wall and designed when so engaged, to impinge upon the retaining member from without tending to limit rotation of said member and provide flexibility in operation.

3. In a rail chair and in combination with a rail section, a rail plate formed with a rail engaging wall and in spaced relation, a rail abutting wall, a rail retaining member formed to loosely engage with the rail plate and the rail abutting wall and further adapted to simultaneously and loosely engage with said rail, a combined locking and lever member for the retaining member and the rail abutting wall.

4. In a rail chair and in combination with a rail section, a rail plate formed with a rail retaining wall adapted to loosely engage with the rail, a rail abutting wall spaced from the retaining wall, a rail retaining member formed for simultaneous loose engagement with the rail plate, the rail abutting wall and the rail, a combined self-locking and lever member for the retaining member and the rail abutting wall.

5. In a rail chair the combination with the sides of the chair and a detachable rail holding member flexibly associated with the chair, of a self-locking tamper-proof key simultaneously engaging with the side of the chair and with the holding member interiorly and exteriorly.

6. In a rail chair the combination with a side or wall of the chair and a rail holding member detachably associated with said wall, of a combined self-locking anti-tipping key adapted to lock the holding member with the wall from within, while impinging upon said member from without.

7. In a rail chair the combination with a bent

wall or side of the chair and a rail holding member detachably associated therewith, of a combined locking and lever member adapted for simultaneous engagement within the wall and the holding member while engaging externally with the holding member to retain said member in locked spring actuated balanced position relative to a rail in the chair.

8. In a rail chair fastening of the character described and in combination, a rail holding wall, a rail abutting wall in spaced relation, a rail holding member co-operating with the rail abutting wall, a locking key operable in the abutting wall and in the rail holding member to locking position, while engaging with the rail holding member externally to resist rotation or tipping of said member.

9. In a rail chair of the character described, the combination with a rail abutting wall adapted to engage with locking means, and a rail holding member loosely associated with said wall and designed to receive the aforementioned locking means in self-locking position, said means comprising a pin or key adapted for self-locking engagement with the abutting wall and the holding member and further adapted for exterior engagement with the holding member tending to limit tipping thereof.

10. In a device of the character described, the combination with a rail abutting wall and a rail holding member, of a locking key or pin slidably drivable to self-locking position within the holding member and the wall and to contact externally with said member.

11. In a device of the character described and in combination, a rail abutting wall, a rail holding member associated therewith, a locking key adapted for simultaneous self-locking engagement with the wall and the holding member and for abutting contact with the holding member.

12. In a device of the character described and in combination, a rail abutting wall and a rail holding member detachably associated therewith, a "follower" driven tamper-proof key or pin engaging with the wall while interiorly and exteriorly engaging with the holding member, in self-locking position.

13. In a device of the character described, the combination with a suitably bent wall and a co-operating rail holding member, of a "follower" driven locking key engaging with the wall and doubly engaging with the holding member.

14. In a device of the character described, the combination with a rail abutting wall and a rail holding member co-operating with said wall, of a locking key formed to be driven into the wall and the holding member to automatically lock said member from within and while abutting on said member from without, to resiliently limit tipping or rotation of said member, in operation.

15. In a device of the character described, the combination with a rail abutting wall and a rail holding member co-operative with said wall, of a drivable locking key formed for self-locking engagement with the wall and the holding member and anti-tipping contact with the holding member.

ROBERT HILL.
